UNITED STATES PATENT OFFICE.

HARRY A. PALMER, OF JACKSON, MICHIGAN, ASSIGNOR TO REYNOLDS SPRING COMPANY, OF JACKSON, MICHIGAN.

SPRING STRUCTURE.

Application filed January 18, 1922. Serial No. 530,645.

To all whom it may concern:

Be it known that I, HARRY A. PALMER, a citizen of the United States, residing at Jackson, in the county of Jackson and State of Michigan, have invented new and useful Improvements in Spring Structures, of which the following is a specification.

This invention relates to spring structures.

Spring structures for automobile seats are generally built by manufacturers and sold without upholstering material applied to the structure. The purchaser of the spring structure applies an upholstered covering thereto, or has it done by an upholsterer.

15 It is therefore one object of my invention to provide a spring structure to which the upholstering material may be readily applied by an upholsterer or manufacturer of automobiles or the like.

20 Another object resides in the provision of a spring structure embodying among other characteristics a simple and inexpensive base frame to which the supporting bars which support the body springs may be attached 25 in any suitable manner, and to which the marginal edge of the skirt or upholstered covering may be readily secured in position against undue wear or tearing and against accidental detachment incident to the 30 bound of the body springs subsequent to compression due to the weight of the rider, or because of uneven roadways.

With the above and other objects in view, the present invention consists in the combination and arrangement of parts as herein-after more fully described and particularly pointed out in the appended claims, it being understood that changes may be made in the form, proportion, size and minor details 40 without departing from the spirit of the invention or sacrificing any of the advantages thereof.

In the drawings:

Fig. 1 is a fragmentary sectional view illustrating the invention with the marginal edge of the skirt in the groove ready to be secured therein.

Fig. 2 is a similar view illustrating the skirt secured in the groove of the base frame.

50 Fig. 3 is a detail perspective view of a portion of the base frame.

Fig. 4 is a plan view of the base frame and spring supporting bars.

Referring now more particularly to the

accompanying drawings, the reference character A indicates, generally, a base frame composed of a strip of sheet metal folded upon itself to provide continuous superimposed upper and lower outwardly opening grooves 5 and 6.

The character 7 indicates a pair of U-shaped supporting bars in which the base convolutions of the body springs 8 are clamped, as indicated at 9. The ends of these spring supporting bars are flattened and turned into hooks 9 adapted to loosely hook over the upper wall 10 of the upper groove 5, whereby to support the body springs of the base frame. In the process of assembling the structure, the necessary 70 number of springs to make up a row have their base convolutions clamped in a pair of the spring supporting bars 7. The ends of the bars 7 are then formed into hooks and the bars with the springs secured thereto 75 are hooked over the upper wall of the groove 5 along which upper wall, the spring supporting bars are slidably adjustable. The hooked ends of these bars may remain loose 80 on the frame or after adjustment thereon they may be fixedly secured thereto, if desired, as by a pinching operation.

An upholstering covering is indicated at 10 and may have its marginal edge wrapped onto or have sewed thereinto a spline, such 85 as wire, wood, fiber, cord or the like 12. The marginal edge of the skirt with or without the spline therein, is drawn over the upper U-shaped member 5 and fitted in the lower groove 6 of the base frame when the lower wall 13 of the lower groove 6 is bent or forced upwardly toward the upper wall 14 of the lower groove 6 onto the skirt to substantially close the lower groove to bind 90 the skirt within the said lower groove 95 against accidental disconnection from the base frame.

What I claim is:

1. In a spring structure a base frame composed of a strip of sheet metal folded upon itself to form superimposed outwardly opening grooves, pairs of U-shaped spring supporting bars having the opposite walls at the ends thereof brought together and bent to form hooks of double thickness adapted 100 to rest upon the top of the base frame and hook into the uppermost groove, springs 105 mounted on said bars, and an upholstering

covering including a skirt having its marginal edge secured in the lowermost groove of the base frame.

2. In a spring structure, a base frame composed of a strip of sheet metal folded upon itself to form superimposed outwardly opening grooves, pairs of spring supporting bars each having hooks at its ends adapted to extend over and hook into the uppermost

groove of the base frame, springs mounted 10 on said bars, and an upholstering covering including a skirt adapted to conceal the hooked ends of said bars and having its marginal edge secured in the lowermost groove of the base frame.

In testimony whereof I have hereunto affixed my signature.

HARRY A. PALMER.
